UNITED STATES PATENT OFFICE.

JAMES DALZELL, OF PITTSBURG, PENNSYLVANIA.

DESIGN FOR GLASSWARE.

SPECIFICATION forming part of Design No. 12,647, dated January 3, 1882.

Application filed September 2, 1881. Term of patent 7 years.

To all whom it may concern:

Be it known that I, JAMES DALZELL, of Pittsburgh, in the county of Allegheny and State of Pennsylvania, have invented a new and useful Improvement in Design for Glassware; and I do hereby declare the following to be a full, clear, and exact description thereof, reference being had to the accompanying drawings, forming a part of this specification, in which—

Figure 1 is a perspective view of my improved design, and Figs. 2 and 3 are sectional views of the same.

My design in glassware consists of a glass vessel formed after the shape of a wheelbarrow, as represented in the accompanying drawings, which vessel is to be used for salt-cellars, match-safes, and similar purposes.

In the drawings the wheelbarrow shape is fully shown. The vessel being made in two parts, the body is of pressed glass and the

wheel formed in a separate piece of glass or other substance. The vessel may, however, be formed in one piece.

The vessel may be ornamented by reliefs, if desired.

I claim—

1. As a new design in glassware, a glass vessel formed in the shape of a wheelbarrow, as represented in the accompanying drawings.
2. As a new design in glassware, a glass vessel formed in the shape of a wheelbarrow, said vessel being ornamented in relief, as represented in the accompanying drawings.

In testimony whereof I have hereunto set my hand.

JAMES DALZELL.
